C. E. SKAGGS

ANTICREEPING DEVICE FOR RAILS

Filed Jan. 25, 1927

UNITED STATES PATENT OFFICE.

CHARLES E. SKAGGS, OF BAY POINT, CALIFORNIA.

ANTICREEPING DEVICE FOR RAILS.

Application filed January 25, 1927. Serial No. 163,342.

My invention relates to improvements in anti-creeping devices for rails and it consists in the combinations, constructions, and arrangements hereinafter described and 5 claimed.

An object of my invention is to provide an anti-creeping device, which may be applied to a railroad track without altering the construction of the latter and which may be 10 secured in place with the same bolts and spikes that are now employed, no additional bolts and spikes being necessary.

A further object of my invention is to provide a device of the type described which is 15 extremely simple in construction, and which is durable and efficient for the purpose intended.

Other objects and advantages will appear in the following specifications and the novel 20 features of the invention will be particularly pointed out in the appended claims.

My invention is illustrated in the accompanying drawing forming a part of this application in which

25 Figure 1 is a perspective view of the device as shown operatively applied to a track.

Figure 2 is a vertical section through the device, and

30 Figure 3 is a horizontal section through the device taken just below the head of the rail.

In carrying out my invention I make use of a rail 1 having a head 2, a web 3 and a flange 4. Angle bars 5 are used for joining 35 rail sections together. The rail 1 is mounted upon ties 6 and is secured thereto by means of spikes 7. Tie plates 8 are disposed between the rail and the ties in the usual manner. The parts thus far described form no 40 part of my invention except in so far as they cooperate with the parts now to be described.

The anticreeper comprises an angle-shaped bar 9 which has a portion 10 for overlying the top of the flange 4 and a portion 11 45 which has recesses 12 for receiving the tie plates 8. Figure 2 clearly shows how the portion 10 has spike openings 13 therein and how the portion 11 is spaced from the edge of the base 4 for permitting the spikes 7 to 50 pass between the portion 11 and the base 4 and on into the tie 6.

The bar 9 is provided with a shoulder 14 which abuts against the end of the angle bar 5. A lug 15 extends from the bar 9 and 55 has an opening 16 therein, see Fig. 2, for receiving a bolt 17.

From the foregoing description of the various parts of the device, the operation thereof may be readily understood. If desired the rail section 1 may have a bar 9 extend in the 60 opposite direction to that shown in Figure 1, in addition to the bar 9 as shown and in this way the rail will be prevented from creeping in either direction. The angle iron bar 9 is long enough to extend over the desired number of ties for assuring the rail 65 against creeping. The recesses 12 snugly receive the tie plates 8 and the walls of the openings 13 bear against the spikes 7 for preventing movement of the bar 9 with respect to the ties and the spikes. The bar in turn is connected with the rail by means of the bolt 17 and thus prevents the rail from 70 creeping. One of the principal advantages 75 of the device lies in the fact that the device may be applied to the rail without any additional fastening means being necessary other than that which is already used.

I claim:

1. The combination with a rail section, a 80 splice bar, ties, tie plates and means for securing said rail section to said ties and said splice bar to said rail section, of an anti-rail creeping device secured to said ties and said rail section by said securing means and means 85 carried by said device for engaging with said tie plates.

2. The combination with a rail section, means for securing said rail section to another rail section, ties, tie plates, and means for securing said rail section to said ties, of an anti-creeping device secured to said ties by the means securing said rail section to said ties, and secured to said rail section by the means for securing two rail sections together, and 90 means carried by said device for engaging with said tie plates.

3. A device of the type described comprising an angle-shaped bar having spike receiving openings in one leg thereof and tie plate receiving recesses in the other leg thereof, and a lug having a bolt receiving opening therein. 100

4. The combination with rail sections, splice bars for securing said rail sections together, bolts connecting said splice bars to said rail sections, ties, tie plates, and spikes for securing said rail sections to said ties, of an anti-creeping device, having openings therein for receiving said spikes, having recesses therein for receiving said tie-plates, and having a lug 105 with an opening therein for receiving said bolts. 110

5. A device of the type described comprising an angle shaped bar having spike receiving openings in one leg thereof and tie plate receiving openings in the other leg thereof, 5 and a lug extending from said second leg and having a bolt receiving opening therein.
6. A device of the type described comprising an angle shaped bar having spike receiving openings in one leg thereof and tie-plate 10 receiving recesses in the other leg thereof, a splice bar engaging shoulder on one of said legs and a lug extending from the other of said legs and having a bolt receiving opening therein.
- 15 7. The combination with a rail section, and splice bar, ties, and means for securing said rail section to said ties and said splice bar to said rail section, of an anti-rail creeping

device secured to said ties and said rail section by said securing means, and means carried by said device for engaging the end of said splice bar.

8. The combination with a rail section, splice bars for securing said rail section to another rail section, a bolt connecting said splice bars to said rail section, ties, tie-plates, and spikes for securing said rail section to said ties, of an anti-creeping device, having openings therein for receiving said spikes, having recesses therein for receiving said tie-plates, having a shoulder thereon for engaging the end of said splice bars, and having a lug with an opening therein for receiving said bolt.

In testimony whereof I affix my signature.
CHARLES E. SKAGGS.
